UNITED STATES PATENT OFFICE

CHARLES A. SCHALLIS, OF ERNESTVILLE, LINCOLN PARK, AND CHARLES W. DANN, OF EAST ORANGE, NEW JERSEY, ASSIGNORS TO THOMAS A. EDISON, INCORPORATED, OF WEST ORANGE, NEW JERSEY, A CORPORATION OF NEW JERSEY

DESIGN FOR A COFFEE MAKER OR LIKE ARTICLE

Application filed August 6, 1930. Serial No. 36,580. Term of patent 14 years.

To all whom it may concern:

Be it known that we, CHARLES A. SCHALLIS, a citizen of the United States, and a resident of Ernestville, Lincoln Park, in the county of Morris and State of New Jersey, and CHARLES W. DANN, a citizen of Germany, and a resident of East Orange, in the county of Essex and State of New Jersey, have invented a new, original, and ornamental Design for Coffee Maker or like Article, of which the following is a specification, reference being had to the accompanying drawing, forming a part thereof.

In the drawing:

The figure is a perspective view of a coffee maker or like article showing our new design.

We claim:

The ornamental design for a coffee maker or like article, substantially as shown.

CHARLES A. SCHALLIS.
CHARLES W. DANN.
